(57) **CLAIM**

The ornamental design for a water bottle with straw, as shown and described.

DESCRIPTION

FIG. 1 is a top, front, and left side perspective view of a water bottle with straw showing our new design in a closed state;

FIG. 2 is a top, rear, and right side perspective view thereof, showing the design in the closed state;

FIG. 3 is a bottom, front, and right side perspective view thereof, showing the design in the closed state;

FIG. 4 is a top, front, and right side perspective view thereof, showing the design in an open state;

FIG. 5 is a top, rear, and left side perspective view thereof, showing the design in the open state;

FIG. 6 is a right side view thereof, showing the design in the open state;

FIG. 7 is a front side view of thereof, showing the design in the closed state;

FIG. 8 is a rear side view thereof;

FIG. 9 is a left side view thereof;

FIG. 10 is a right side view thereof;

FIG. 11 is a top plan view thereof;

FIG. 12 is a bottom plan view thereof;

FIG. 13 is an enlarged view of the encircled portion '13' in FIG. 2 thereof; and,

FIG. 14 is an enlarged view of the encircled portion '14' in FIG. 4 thereof.

The broken lines are for the purposes of illustrating portions of the water bottle with straw that form no part of the claimed design.
